Filed July 5, 1973, Ser. No. 376,385

Term of patent 14 years

Int. Cl. D13—03

U.S. Cl. D26—1 R

FIG. 1 is a front elevation view of a rubber cover for vehicle multipole connector showing my new design;

FIG. 2 is a side elevation view thereof;

FIG. 3 is a top plan view thereof;

FIG. 4 is a bottom plan view thereof;

FIG. 5 is a sectional view taken along the line 5—5 of FIG. 2 in the direction indicated generally; and

FIG. 6 is a sectional view taken along the line 6—6 of FIG. 1 in the direction indicated generally.

The rear elevation and opposite side elevation configurations correspond to the views shown in FIGS. 1 and 2, respectively.

I claim:

The ornamental design for a rubber cover for vehicle multipole connector, substantially as shown and described.
